[57] **CLAIM**

The ornamental design for a housing for telephone switchboard, as shown and described.

DESCRIPTION

- FIG. 1 is a front elevational view of a housing for telephone switchboard showing my new design;
 FIG. 2 is a top plan view thereof;
 FIG. 3 is a bottom plan view thereof;
 FIG. 4 is a rear elevational view thereof;
 FIG. 5 is a right side elevational view thereof, the left side being a mirror image; and,
 FIG. 6 is an enlarged cross-sectional view thereof taken on line 6—6 of FIG. 1.

UNITED STATES PATENT AND TRADEMARK OFFICE
CERTIFICATE OF CORRECTION

PATENT NO. : Des. 355,419
DATED : February 14, 1995
INVENTOR(S) : Seiji Namba

It is certified that error appears in the above-identified patent and that said Letters Patent is hereby corrected as shown below:

Title page, after [*] Notice, delete "The portion of the term of this patent subsequent to Jul. 17, 2008 has been disclaimed." and insert therefore
--The portion of the term of this patent subsequent to Jul. 19, 2008 has
been disclaimed.--

Signed and Sealed this
Fourth Day of July, 1995

Attest:

BRUCE LEHMAN

Attesting Officer
